UNITED STATES PATENT OFFICE.

FREDERIC AUMONIER, OF LONDON, ENGLAND.

DESIGN FOR WALL-PAPER.

SPECIFICATION forming part of Design No. 22,970, dated December 19, 1893.

Application filed November 20, 1893. Serial No. 491,522. Term of patent 3½ years. Registered in England December 21, 1892, No. 204,614.

To all whom it may concern:

Be it known that I, FREDERIC AUMONIER, (trading as W.M. WOOLMANS & CO.,) a subject of the Queen of Great Britain, and a resident of 110 High Street, near Manchester Square, London, England, have invented a new and original Design for Wall-Paper, (registered in Great Britain on December 21, 1892, No. 204,614,) of which the following is a specification.

This design for wall paper is represented by the accompanying drawing showing frieze and filling. The frieze consists of oak and fern leaves and scroll stems terminating in drooping clusters of flowers at intervals, the partition lines having a center of dots. The other part or filling is composed of wavy lines or leaves inclosing vertically other fern leaves and skeletons of leaves surmounted by three

flower heads whose stems pass through a 20 closely arranged leaf like device. Alternately between the foregoing the spaces are filled with curled scrolls inclosing other leaves of a conventional character surmounted with a flower in a heart-shaped opening, the edge of 25 which is formed of curled scrolls rising approximately to a point.

I claim—

The design for wall paper substantially as herein shown and described.

The 10th day of March, 1893.

FREDERIC AUMONIER.
